US0D1029714S

(12) **United States Design Patent** (10) **Patent No.:** **US D1,029,714 S**
(45) **Date of Patent:** **** Jun. 4, 2024**

(54) **SPOKED ROTOR**

(71) Applicant: **Nidec Motor Corporation**, St. Louis, MO (US)

(72) Inventors: **John M. Tucker**, St. Louis, MO (US); **Lunjie Lu**, Chesterfield, MO (US)

(73) Assignee: **Nidec Motor Corporation**, St. Louis, MO (US)

(**) Term: **15 Years**

(21) Appl. No.: **29/804,279**

(22) Filed: **Aug. 19, 2021**

(51) **LOC (14) Cl.** **13-02**

(52) **U.S. Cl.**

USPC **D13/122; D15/5**

(57) **CLAIM**

The ornamental design for a spoked rotor, as shown and described.

DESCRIPTION

FIG. 1 is a perspective view of a spoked rotor embodying our design;

FIG. 2 is an end elevation view of the spoked rotor as shown in FIG. 1, with the opposite end view being a mirror image thereof; and,

FIG. 3 is a side elevation view of the spoked rotor as depicted in FIGS. 1 and 2, with the opposite side view being a mirror image thereof.

1 Claim, 2 Drawing Sheets
